CLAIM

The ornamental design for a security device, as shown and described.

DESCRIPTION

FIG. 1 is a perspective view of a security device according to our design;

FIG. 2 is a top view of the security device shown in FIG. 1; FIG. 3 is a bottom view of the security device shown in FIG. 1;

FIG. 4 is a front view of the security device shown in FIG. 1;

FIG. 5 is a back view of the security device shown in FIG. 1;

FIG. 6 is a right side view of the security device shown in FIG. 1; and,

FIG. 7 is a left side view of the security device shown in FIG. 1.

In the drawings, the broken lines depict environmental subject matter only and form no part of the claimed design.
